UNITED STATES PATENT OFFICE.

HOWARD J. MURRAY, OF BROOKLYN, NEW YORK.

RECIPROCATING MOTOR.

1,268,265.

Specification of Letters Patent. Patented June 4, 1918.

Application filed September 15, 1914. Serial No. 861,807.

To all whom it may concern:

Be it known that I, HOWARD J. MURRAY, a citizen of the United States, and resident of the borough of Brooklyn, in the county of 5 Kings and State of New York, have invented certain new and useful Improvements in Reciprocating Motors, of which the following is a specification.

My invention relates to an electromagnetic reciprocating motor in the form of a multiple armature magnet and while the invention is of general application, the embodiment thereof herein described is particularly designed for use in connection with a gear shifting or similar mechanism of the type which depends for its operation upon the throw of controlling members.

One of the objects of the invention is to provide a simple form of electrically energized motor designed to move a reciprocating member at will, in either of its directions of movement with the least expenditure of energy and collateral to this is the providing of such a motor substantially free 25 from mechanically actuated parts and the disadvantages incidental thereto.

In attaining this object, I utilize the principle underlying the generation of force in a freely movable conductor disposed in an electromagnetic field of force and positioned transversely of the lines of force thereof when an electric current is passed through the conductor. One means by which this force may be obtained is to arrange a pair 30 of magnets for creating two parallelly disposed and spaced apart fields of magnetic force and by mounting, for reciprocal movement relative to said fields, a pair of uniplanarily wound armatures disposed between the poles of said magnets and to so arrange 35 the windings that passing a current through either armature will cause the same to move in one of its reciprocatory directions of movement for a prescribed distance.

40 Among the other objects of the invention are to provide a means for automatically breaking the circuit through any of the armatures when the same has moved into a preset position and to provide means for 45 automatically locking the armature in its preset position.

An object incidental to the embodiment of the invention illustrated is to provide a safety control device for use with motor 50 vehicle driving mechanisms which device is designed to return parts thereof to their

normal inoperative position in case of accident or the failure of the source of operative power and is particularly designed to prevent any actuation of the gear shifting 60 mechanism while a controlling switch, such as the clutch connecting the motive power with the driving mechanism, is in its operative position.

Various other objects and advantages of 65 the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the drawings:

Figure 1 is a side elevation of one form of my invention with the casing cover removed and end parts broken away for convenience;

Fig. 2 is a plan view of the device shown in Fig. 1 with parts broken away to show 80 details of construction;

Fig. 3 is a transverse sectional view taken on the line 3—3 of Fig. 1; and

Fig. 4 is a diagrammatic view of the mechanism and its electrical connections. 85

In connection with the device illustrated the invention will be described as a gear shifting mechanism but it will be obvious that the device may be used in connection with any character of machine, which requires the shifting of its different parts. When used in connection with an automobile the device may be mounted in any desirable location on the vehicle and is enclosed within a suitable casing 1, preferably 90 made of aluminum and including a removable side cover 2 affixed thereto, as is usual with devices of this character. The casing is designed to contain the mechanism in the smallest possible space as it is desirable to 95 fill all open spaces therein with some form of insulating packing.

The mechanism for generating a pair of parallel spaced apart fields of electromagnetic fields of force is positioned in the casing and preferably is formed of a pair of horse-shoe magnets 3 and 4 disposed edge-wise on their sides and made up of laminated strips fastened together and fixed to the casing by bolts 5. The magnets are energized through the medium of field windings 6 and 7 which are wound in opposite

directions about their crotches and connected by a conductor 8 so that the adjacent ends of the magnets on one side of the armature, hereinafter described, have opposite polarity as indicated by the symbols S and N.

A pair of parallelly disposed armatures 9 and 10 are mounted for reciprocatory movement transversely of the fields of force and between the poles of the magnets. Each armature is formed of an open sided elongated box 11 preferably square in cross-section and having a magnetic insulating block 12 preferably made of aluminum or brass extending between and bracing the opposite longitudinal sides relative to each other at the center thereof. Gear shifting rods 13 and 14 project from opposite ends of each box, and extend through bossed openings 15 in the ends of the casing to support and guide the armatures in their reciprocatory movements.

The armatures are maintained in their centrally disposed position by balanced springs 16 and 17 positioned on each of the rods 13 and 14 between the ends of the casing and each of the boxes 11.

Each box preferably contains a core of laminated plates 18 which prevent the flux in the armature from saturating any particular section thereof. Each core is provided with two parallel rows of perforations 19 extending therethrough in a direction transversely to the lines of force between the poles of the magnets. A conductor forming an inductor 20 enters the armature 9 at one end of one of the rows, passes the centrally disposed spacing block 12 and is threaded through the first perforation therebeyond, is looped back upon itself to the first perforation on the opposite side of the block and then back to the second aperture and is thus looped alternatively through the succeeding perforations outwardly of the block thereby to form, of each core, a uniplanarily wound armature. The conductor may then be brought back to the beginning of the next row of perforations and this second row wound as the previously described row, thus forming two planes of windings, but it is obvious that any number of these planes of windings may be formed in each armature. A conductor 21 is similarly wound through the other armature 10 in the same manner. In case only one field is used the armature is preferably wound in a manner such as has been described first about a center adjacent one end of the armature and then wound in a reverse direction about a center adjacent the other end so that the currents flowing in the windings will always be in the same direction within the outlines of the armature whereby the field will act on the armature for the full length of the same.

The rods 13 and 14 may be so arranged

and connected to the conventional transmission box, (not shown, but commonly found on automobiles) that the movement of each rod in either direction longitudinally will connect a set of gears so that the two rods 70 in the device illustrated may control four speeds, such as three speeds forward, and one reverse. Each armature is locked in its shifted position in either direction by a suitable clutch and for this purpose a locking plate 22 having a centrally disposed transverse slot 22' is fixed to the underside of each armature and the slot of one or the other plates is engaged by the plunger armature 23 of a locking electromagnet 24 75 80 which is contained in a shell 25 forming part of the casing and positioned centrally beside the armatures between the magnets.

The armature of the magnet 24 is normally held in retracted position out of engagement with the plate by means of a coiled spring 26 bearing on the locking magnet and a head 27 on the plunger armature. The locking magnet is so wound that energizing the same will cause the armature 90 thereof to move into engagement with the plate and to hold the armature in shifted position by engaging the end of the plate from movement under tension of the springs 16 and 17. On moving into its locking position the armature 23 is caused to break the circuit through the field magnets and their armatures and for this purpose a two point circuit breaker 28 of any suitable form is mounted in the shell 25 in position to 100 be actuated by the movement of the head 27.

The supply of current to the field coils of the magnet, to the armatures and to the locking electromagnet is controlled by a switch 29 which may be mounted on top 105 115 of the steering wheel of the vehicle or in any other convenient position.

A suitable source of electric power 30 is connected through a switch 31 to a two blade lever 32 constituting the hand control of the switch 29, which lever is pivoted at one end 33 for universal movement. A pair of parallel segmental contact plates 34 and 35 are disposed concentrically of the pivoted end of the lever and constitutes a 115 continuation respectively of the conductors 36 and 37 leading from the source 30. An arcuate line of contacts, in the diagrammatic view shown to be twelve in number, arranged in pairs, and lettered progressively 120 from *a* to *l*, is disposed to the outside of the plates 34 and 35.

One set of contacts *k* and *l* may be connected to an electric starter and another set *g* and *h* may be connected to some other 125 mechanism such as an electrically energized braking device.

A field circuit is provided, which includes conductor 38 leading from the plate 35 through one of the points of the circuit 130

breaker 28, through first one and then the other of the field windings and then back to the plate 34 through the conductor 39. The current for the locking magnet 24 is shunted off this circuit by the conductors 40 and 41 and the current is maintained constant in direction through this magnet irrespective of the direction of current through the armature windings. Contacts 10 *a, d, f* and *i* are connected to an armature circuit which in the device illustrated includes a conductor 42 containing a controlling switch 43 connected with the usual clutch on automobile driving mechanism 15 and so arranged that the circuit is broken when the clutch is "in." The conductor 42 contains the other point of the circuit breaker 28 and leads to a shunt 42' from which the current passes through the armatures 9 and 10 from one of which armatures (as 9) the conductor 20 leads back to the switch and is connected to the contacts *b* and *c* thereof. The conductor 21 leads from the other armature 10 back to the switch 25 and is connected to the contacts *e* and *j*.

The lever 32 has a pair of spring contacts 44 and 45 insulated from each other and adapted to bear on the plates 34 and 35 respectively when the lever is held between any pair of the lettered contacts.

These conductors are preferably contained in a cable 46 leading from the switch 29 to a distribution box 47 mounted on the outside of the casing from which the several 35 conductors lead to their respective windings and magnets, and to the clutch circuit breaker.

In operation and with the several parts in the position shown, the switch lever may 40 be moved to engage any of the sets of contacts desired, as for instance to engage the contacts *k* and *l* to actuate a self starter. In this case the current from the source 30 will pass through the lever 32 to the contacts *k* and *l* and directly to the starter. The lever would then be lifted into a raised 45 position to clear the line of contacts and rotated to engage one of the sets of speed controlling contacts. For instance, should it be desired to run on first speed the lever 50 could be moved into position to engage and be held by the resilient contacts *e* and *f*. This positioning of the lever would connect the plates 34 and 35 with the source of energy and a field circuit would be completed 55 from plate 34 through conductor 39, the field windings of each of the magnets, through one of the points of the circuit breaker 28, through conductor 38, lever 32 to plate 35 and the source of energy. At 60 the same time an armature circuit is shunted from contact *e* through the conductor 21, armature 10, the other point of the circuit breaker 28, the clutch controlled member 43 and conductor 42 to contact *f*.

This connection will cause each of the magnets to form a field of force and the windings are arranged so that the lines of force therein will be opposite in direction. The windings in the armature are so arranged that there will be a reaction between one end of the armature and the adjacent field and a reaction between the other end of the armature and its adjacent field, both forces coacting to move the armature in one direction and thus advance one of the rods 13 or 14 into position to move the gears into mesh on the first speed. The shunted circuit through the locking magnet 24 will cause the plunger armature 23 to move into engagement with the locking plate 22 and to project farther against the tension of the spring 26 as the plate passes the armature. This further movement of the locking armature adjacent the end of the travel 70 of the armature 10 will cause the circuit to be broken through the armature and through the magnets but the circuit will be maintained through the locking magnet as long as the lever is in engagement with a 75 pair of contacts. Deenergizing the fields and armature 10 will bring the armature to a stop in its shifted position and the armature will be locked in this position as long as current is flowing through the magnet 25. 80 85 90

Lifting the switch lever out of engagement with the contacts *e* and *f* deenergizes the locking magnet permitting the spring 26 to withdraw the armature from its locking position and permitting one of the 100 springs 16 or 17 to return the armature 10 to its centered neutral position. It will be noted that this occurs whenever the switch lever is raised from any one of its positions so that when passing from one speed to another all parts of the gear shifting mechanism are in their normal inoperative positions.

From this specific tracing of one of the sets of circuits, it will be obvious from 110 following the diagram of Fig. 4 that each of the rods may be shifted longitudinally in either direction by making the proper contact with the switch lever. It will be noted for instance that bringing the lever 115 into engagement with the contacts *i* and *j* will cause the current to be reversed through the armature 10 to draw this armature in a reverse direction to obtain for instance a reverse speed.

By means of a device of this character, I am enabled to provide a simple and compact mechanism for controlling the different operating parts of machines to which a device of this character is applicable and to provide an arrangement whereby relatively small magnets may be used to shift machine parts of relatively large mass. The device may be economically operated for the current is shut off from the field magnet 120 125 130

and armature automatically as soon as the armature has completed its work, and it is obvious that the locking magnet may be so wound as to require but little current to maintain the magnetic clutch in its operatively circuit breaking and locked position.

The mechanism described is intended generally for use as a safety device on self propelled vehicles and with this object primarily in view the parts are so arranged that in case of any accident to the mechanism the different parts are automatically and promptly returned to their initial inoperative position and in this way the possibility of running the machine without absolute control is eliminated. Should anything go wrong the vehicle would merely stop.

As the control switch lever can be in but one position at a time, it will be seen that it is impossible to make improper connections. For instance, when the circuit is completed through the self starter, the gears are in their normal inoperative position and the transmission will be inoperative until the lever is moved into a position to positively bring the gears of the transmission into mesh. Also the gears are unmeshed whenever the lever is being moved from the contacts controlling one speed to the contacts controlling another of the speeds, so that irrespective as to the number of shift rods employed, but one part can be in connecting position at a time.

It is obvious that a pre-selected arrangement of the gears or other mechanism actuated by this device may be attained while the device is inactive by shifting the lever 32 into engagement with the desired pair of lettered contacts while the clutch controlling the switch 43 is "out". Completing the circuit through the several parts by throwing in the clutch, will cause the device to actuate under the pre-selected condition of the several parts.

While I have shown and described and have pointed out in the annexed claims certain novel features of my invention it will be understood that various changes in the form and details of the device illustrated, such as providing separate locking means either electrical or mechanical for each armature, multiplying the number of armatures and their actuated mechanism or providing a series arrangement instead of the shunt arrangement illustrated may be made. It is also obvious that various other changes, omissions and substitutions in the particular form of the invention illustrated and in its operation may be made by those skilled in the art without departing from the spirit of the invention.

Having thus described my invention, I claim:

1. A gear shifting device comprising a casing, a pair of parallelly disposed horse-

shoe magnets mounted in said casing, windings on said magnets arranged to form electromagnetic fields of force with oppositely disposed polarity, a pair of armatures extending between the poles of said magnets, rods extending from said armatures through said casing, mounting the armatures for reciprocatory movement relative to the fields of force, each armature having a uniplanar winding extending transversely of the lines in the electromagnetic fields of force, an electrically actuated locking mechanism for holding either armature at the limit of its movement in either reciprocatory direction and selective means for completing a circuit through said locking mechanism, through said magnet windings and through the windings of either of said armatures.

2. A gear shifting device comprising a casing, a pair of parallelly disposed horseshoe magnets mounted in said casing, windings on said magnets arranged to form electromagnetic fields of force with oppositely disposed polarity, a pair of armatures extending between the poles of said magnets, rods extending from said armatures through said casing mounting the armatures for reciprocatory movement relative to the fields of force, an electrically actuated locking mechanism for holding either armature at the limit of its movement in either reciprocatory direction, selective means for completing a circuit through said locking mechanism through said magnet windings and through the windings of either of said armatures and a circuit breaker coacting with said locking mechanism for interrupting the circuit through said windings.

3. A gear shifting device comprising a casing, a pair of parallelly disposed horseshoe magnets mounted in said casing, windings on said magnets arranged to form electromagnetic fields of force with oppositely disposed polarity, a pair of armatures extending between the poles of said magnets, rods extending from said armatures through said casing mounting the armatures for reciprocatory movement relative to the fields of force, an electrically actuated locking mechanism for holding either armature at the limit of its movement in either reciprocatory direction, selective means for completing a circuit through said locking mechanism, through said magnet windings and through the windings of either of said armatures, a circuit breaker coacting with said locking mechanism for interrupting the circuit through said windings and manually actuated means for interrupting the circuit through said locking mechanism.

4. In a device of the class described, the combination with a pair of spaced apart mechanisms, each capable of generating an electromagnetic field of force parallel to 130

each other, a pair of armatures disposed in parallelism and each forming part of an electric circuit and mounted for reciprocatory movement between and into said fields 5 transversely of their lines of force and selective means for closing either circuit to cause at will a movement of either armature.

5. In a device of the class described, the combination with an electrically energized 10 mechanism capable of generating a relatively stationary electromagnetic field of force, of an armature mounted for reciprocatory movement centrally across said field, said armature being wound with certain of 15 its coils disposed in a plane parallel to the line of movement of the armature and disposed to cross the lines of force and co-operatively arranged relative to said field whereby the armature will be moved in one 20 direction when a current is passed therethrough, and a source of electric energy connected directly with said armature.

6. In a device of the class described, the combination with an electrically energized 25 mechanism capable of generating a relatively stationary electromagnetic field of force, of an armature mounted for reciprocatory movement in said field, said armature being wound with certain of its coils disposed 30 to cross the lines of force and co-operatively arranged relative to said field whereby the armature will be moved in one direction when a current is passed therethrough, a circuit breaker, and an electromagnet operatively connected to the circuit breaker for 35 automatically intercepting the current therethrough and through the mechanism.

7. In a device of the class described, the combination with an electrically energized 40 mechanism capable of generating a relatively stationary electromagnetic field of force, of an armature mounted for reciprocatory movement in said field, said armature being wound with certain of its coils disposed 45 to cross the lines of force and co-operatively arranged relative to said field whereby the armature will be moved in one direction when a current is passed therethrough, a circuit breaker actuated by the movement 50 of said armature into a preset position for automatically intercepting the current therethrough and through the mechanism, and a locking means for holding said armature in place after it has moved a preset distance 55 under the influence of the magnetic field and the lines of force generated by the current through said armature.

8. In a device of the class described, the combination with a pair of mechanisms, each 60 capable of generating a field of force, the line of force in one of said fields being in opposite direction to the lines in the other field, an armature extending between and into both fields, said armature being wound 65 with an electric conductor disposed in planes

perpendicular to the fields and means for passing a current through said conductor.

9. In a device of the class described, the combination with a horse-shoe magnet, of a pair of armatures disposed between the poles 70 of the magnet and movable longitudinally across the lines of force thereof, each of said armatures including an electric conductor disposed in parallel planes, means for directing the current through one of the conductors in one direction and through the other conductor in the opposite direction and means for controlling said currents.

10. In a device of the class described, the combination with a horse-shoe magnet, of an 80 armature disposed between the poles of the magnet and movable longitudinally across the field of force thereof, said armature including an electric conductor arranged in a coil which is disposed in a plane longitudinally of the armature and perpendicular to the field of force.

11. In a device of the class described, the combination of a pair of spaced apart horse-shoe magnets arranged with their fields of 90 force parallel to each other, an armature disposed between the poles of the magnets and movable transversely of the fields, the magnets having opposite polarity on each side of the armature and said armature having 95 windings extending from one field to the other when the armature is in normal position.

12. In a device of the class described, the combination of a field magnet, a wound 100 armature mounted for reciprocatory movement and operatively placed relative to said field magnet whereby passing an electric current through said magnet and armature will cause the armature to move relative to the 105 magnet in one of its longitudinal directions and a manually actuated selective switch designed to be moved at will from an inoperative position into an actively disposed position for regulating the current through said 110 magnet and armature to control the direction of movement of the armature.

13. In a device of the class described, the combination of a field magnet, a wound armature mounted for reciprocatory movement 115 and operatively placed relative to said field magnet whereby passing an electric current through said magnet and armature will cause the armature to move relative to the magnet in one of its longitudinal directions, a manually actuated selective switch for regulating the current through said magnet and armature to control the direction of movement of the armature and balanced springs acting on said armature tending to return the same to 120 its normal position when the current is interrupted through the magnetic locking device or armature.

14. In a device of the class described, the combination of a pair of parallelly disposed 130

electro-magnets with their poles oppositely disposed, a wound armature mounted for reciprocatory movement and operatively placed relative to said magnets so that passing an electric current through the magnets and armature will cause the magnets to react on opposite ends of the armature thereby to move said armature in one of its reciprocatory directions, and means for locking said armature in shifted position.

15. In a device of the class described, the combination of a pair of parallelly disposed electro-magnets with their poles oppositely disposed, a wound armature mounted for reciprocatory movement and operatively placed relative to said magnets that passing an electric current through the magnets and armature will cause one magnet to attract and the other to repel the armature in one of its reciprocatory directions and means operatively controlled by said armature at the limit of its movement to cause said armature to stop its movement.

16. In a device of the class described, the combination with an electromagnetic field of force, an armature operatively mounted for reciprocatory movement in said field, a locking member carried by said armature, an electrically actuated clutch member for engaging said member at the limit of travel of the armature in one direction to lock the same in position and means acting on said clutch to move the same into inoperative position when said clutch member is deenergized.

17. A gear shifting device comprising a casing, a pair of parallelly disposed horse-shoe magnets mounted in said casing, windings on said magnets arranged to form electromagnetic fields of force with oppositely disposed polarity, a pair of armatures extending between the poles of said magnets, rods extending from said armatures through said casing, mounting the armatures for reciprocatory movement relative to the fields

of force, each armature having a uniplanar winding extending transversely of the lines in the electromagnetic fields of force, an electrically actuated locking mechanism for holding either armature at the limit of its movement in either reciprocatory direction, selective means for completing a circuit through said locking mechanism, through said magnet windings and through the windings of either of said armatures and resilient means acting on said armatures tending to return the same to their normal position when disengaged from the locking mechanism.

18. In a device of the class described, the combination with an electrically energized mechanism capable of generating a relatively stationary electromagnetic field of force, of an armature mounted for reciprocatory movement in said field, said armature being wound with certain of its coils disposed to cross the lines of force and cooperatively arranged relative to said field whereby the armature will be moved in one direction when a current is passed therethrough, a circuit breaker actuated by the movement of said armature into a preset position for automatically intercepting the current therethrough and through the mechanism, a locking means for holding said armature in place after it has moved a preset distance under the influence of the magnetic field and the lines of force generated by the current through said armature and resilient means acting on said armature tending to return the same to its initial position when disengaged from the locking means.

Signed at New York city, in the county of New York and State of New York this twelve day of September, A. D. 1914.

HOWARD J. MURRAY.
